[57] CLAIM

The ornamental design for a combined cosmetic pencil and brush, as shown and described.

DESCRIPTION

FIG. 1 is a side elevational view of a combined cosmetic pencil and brush showing my new design;

FIG. 2 is a top plan view thereof;

FIG. 3 is a bottom plan view thereof;

FIG. 4 is an isometric view thereof;

FIG. 5 is an exploded isometric view thereof showing the pencil and a brush which fits in at the bottom;

FIG. 6 is an exploded isometric view thereof with only the pencil exposed; and

FIG. 7 is an exploded isometric view thereof with only the brush exposed.
